MANUFACTURING COMPANY, A CORPORATION OF NEW JERSEY.

SEWING-MACHINE NEEDLE MECHANISM.

1,161,277.

Specification of Letters Patent. Patented Nov. 23, 1915.

Application filed October 7, 1914. Serial No. 865,446.

To all whom it may concern:

Be it known that I, EDWARD B. ALLEN, a citizen of the United States, residing at Bridgeport, in the county of Fairfield and 5 State of Connecticut, have invented certain new and useful Improvements in Sewing-Machine Needle Mechanisms, of which the following is a specification, reference being had therein to the accompanying drawings. 10 This invention has for its primary object to provide means for sustaining a reciprocating and laterally jogging needle which shall be simple and rigid in construction and shall contain a minimum number of 15 joints between the moving parts so as to obviate lost motion between the primary actuating means and the needle and thereby insure precision in the movements of the needle in its coöperation with the loop-taking 20 mechanism.

In the preferred construction of the improvement, the needle-bar is provided with a yoke having a cross-member affording a 25 guide element spaced from and parallel with which is a supporting pin upon which is slidingly mounted a needle-carrying block forked to embrace said cross-bar. Arranged parallel with the needle and fixed relatively to the latter's reciprocating movements is a 30 guide-post engaged by one of the lateral members of said yoke for restraining the needle-bar against rotation relatively to the support of said guide-post. The needle-carrying slide-block has a lateral stud em- 35 braced by the forked depending arm of an elbow-lever fulcrumed upon the support of said guide-post and having a lateral arm provided with a stud which enters the seg- 40 mental guideway of a reciprocating frame having a crank-and-pitman connection with the actuating shaft from which the needle derives its lateral jogging movements, the stud of the needle-carrying slide-block working in its lower positions in either one 45 of two guide-channels rigidly sustained by the support of said guide-post which, in the type of buttonhole sewing machine in which the present improvement is embodied, is adapted to rotate relatively to the actuating 50 shaft and the needle-actuating frame.

In the accompanying drawings, Figure 1 is an elevation showing the needle-actuating mechanism of the present improvement as embodied in a buttonhole machine of the 55 type represented in my United States Patent

No. 945,148, of January 4, 1910, with the bracket-arm represented in dotted lines, and Figs. 2 and 3 are front elevations of the same with the parts in different positions. Fig. 4 is a bottom plan view of the parts of the 60 needle-jogging mechanism beneath the head of the bracket-arm, and Fig. 5 an elevation of a portion thereof with the segmental guide-member in transverse section. Fig. 6 is an elevation of a portion of the needle-jogging means taken from a position at 65 right angles to that of Fig. 5.

Journaled in the overhanging member 1 of the sewing machine bracket-arm is the 70 rotary shaft 2 carrying the disk 3 having the intersecting diametrical grooves 4 entered by the roller-studs 5 of the disk 6 whose hub 7 is secured upon the needle-actuating shaft 8 deriving from the shaft 2, through the trammel device comprising the disks 3 and 75 6, two rotations for each rotation of the shaft 2. The shaft 8 carries a crank-disk 9 provided with a crank-pin 10 connected by means of the pitman 11 with the lateral stud 12 of a collar 13 loosely embracing but re- 80 strained against endwise movement upon the reciprocating needle-bar 14. The needle-bar is journaled above the collar 13 in the bearing boss 15 of the bracket-arm head, and below the same in the rotary bushing 16 85 journaled in the lower member of the bracket-arm head and having fixed thereon the pinion 17 meshing with the rack-bar 18 which is connected with the reciprocating bar 19 slidingly mounted within bearing 90 members 20 and 21 of the bracket-arm. The bushing 16 has at its lower end beneath the bracket-arm head the block 22 from which depends at one side of the needle-bar the post 23 having on the side adjacent the needle-bar a lateral groove or channelway in which is slidingly fitted one of the depend- 95 ing members 24 of a yoke whose connecting cross-member 25 is fixed to the lower end of the needle-bar which latter is by this means 100 confined in fixed angular relation to the post 23 and its supporting block 22.

Passing through one of the depending yoke members 24 and tapped into the other is the transverse screw-pin 26 arranged sub- 105 stantially parallel with the yoke member 25. Slidingly fitted upon the pin 26 is the hub 27 of the needle-carrying block 28 provided with an upwardly extending forked arm comprising the rigid member 29 and the 110

yielding member 30 embracing between them the yoke cross-member 25, as represented more particularly in Fig. 6, the member 30 being reduced in thickness at its base to permit it to yield slightly under the action of the transverse adjusting screw-pin 31 connecting these members and adapted to maintain them snugly in operative engagement with the guiding cross-member 25. The block 28 is formed in its lower end with the usual socket in which is clamped by means of the screw 32 the needle 33. The described mounting of the needle upon the needle-bar is designed to secure facility and accuracy in manufacture of the parts and to insure rigidity of the needle-carrying block with durability of the moving parts in extended use. While the employment of a cylindrical supporting pin 26 insures a close circumferential fit thereon of the similarly apertured block 28, the essential feature of the bearing between these two elements is the close contact between them upon the sides of the bearing pin adjacent to and remote from the yoke cross-member 25. The function of this pin is to support the needle-carrying block and to steady the same against tilting in a plane passing through the axis of the pin 26, while the function of the yoke-member 25, closely embraced by the forked arm 29 of the block 28, is to steady the needle-carrying block from lateral or rocking movement upon such supporting pin.

Extending laterally from the rigid member of the forked arm of the needle-block is the flattened stud-pin 34 adapted to enter alternately the parallel guide-channels 35 of the rigid arm 36 secured by screws 37 upon the supporting block 22. Fulcrumed upon the block 22 above said stud-pin by means of the fulcrum-screw 38 is an elbow-lever having the depending forked arm 39 adapted to embrace the stud-pin 34 when in its upper position, wherein it is retracted from the channels 35, said elbow-lever having a lateral arm 40 carrying the stud-pin 41. The stud-pin 41 enters the circular guide-groove or channel 42 of a rigid ring 43 arranged beneath the bracket-arm head and substantially concentric with the needle-bar and having at one side a hub 44 which is secured by means of the cross-pin 45 upon the lower end of the reciprocating bar 46 which is journaled in suitable bearing apertures of the bracket-arm head. Within the cavity of the bracket-arm head the bar 46 has secured thereon by means of the set-screw 47 the collar 48 from which extends laterally the rigid arm 49 whose outer end 49' is fitted within a suitable guide-aperture 50 of the bracket-arm head. To the arm 49 is pivotally connected by means of the screw-pin 51 the apertured lower end of a link 52 whose apertured upper end is adjustably connected by means of the stud-screw 53

with the slotted crank-arm 54 of well known construction which is secured upon the forward end of the rock-shaft 55 journaled upon the rearward side of the bracket-arm.

Adjustably secured upon the rearward end of the rock-shaft 55 is the split hub 56 of a lateral arm 57 formed in its outer end with a fork 58 embracing the actuating eccentric 59 upon the shaft 2. Through the means just described, the rigid frame comprising the bar 46, the cross-bar 49 and the guide-ring 43, receives from the main-shaft vertical reciprocatory movements of one-half the frequency of the needle reciprocations, the needle slide-block deriving its lateral jogging movements from the ring 43 through the elbow-lever 39, 40 operatively engaging the stud-pin 34 to shift the same alternately into alinement with the rigid guide-channels 35 by which the needle is maintained against lateral movement in its lower positions and while in the work. The ring 43 is shown provided diametrically opposite the boss 44 with a lateral ear 43' which is apertured to loosely embrace a steady-pin 60 secured within and depending from the bracket-arm head.

In the operation of the mechanism, the needle-bar derives, through its trammel-connection with the main-shaft 2, two reciprocations for each rotation of the main-shaft, the needle jogging frame 43 46 49 performing reciprocating movements of one-half the frequency of those of the needle-bar. Through the elbow-lever 39 40 the needle slide-block derives from the actuating frame its sliding movements upon the guide-pin 26 and the guide element afforded by the cross-bar 25 of the needle-bar yoke, these movements being performed only while the needle-bar is in its upper position and while the stud-pin 34 is above the upper ends of the relatively fixed guide-channels 35, as described more fully in my Patents Nos. 945,148, of Jan. 4, 1910 and 1,030,046, of June 18, 1912. In the turning of the stitch-forming elements in stitching around the eye of an eyelet-end buttonhole, the stud-pin 41 obviously follows the turning movements of the bearing sleeve 16, operating in different parts of the groove 42 in the ring 43. Obviously this internally grooved ring constitutes a segmental guide member, the extent of which is determined by the extent of rotary movement of the stitch-forming mechanism. In some machines of this type, as in the present instance, the stitching devices are designed to perform a complete rotation, in which case the segmental extent of the ring 43 is a complete circle; but in other cases, as for instance in the machine of my Patent No. 734,794, of July 28, 1903, the stitching mechanism performs only a semi-rotation, in which case the form of the ring 43

would be that of a segment of little more than a semi-circle.

By the present improvement, the usual spline-and-groove connection between the needle and the rotary bushing in which it is journaled in this type of machine is replaced by a sliding connection comprising the channeled post 23 and yoke member 24 remote from the axis of the needle-bar, thereby providing a strong and durable connection to insure the proper circular relation between the needle and said bushing and the proper operative relation of the needle with the loop-taking means. The guiding of the needle-clamp upon the guide-pin 26 by a connection with the needle-bar yoke cross-bar 25 affords a similar means of restraining the needle-clamp against rocking upon the pin 26. The needle is thus rigidly held against lateral deflection in the plane of the pin 26 by the long bearing thereon afforded by the hub 27 and in a transverse plane by its sliding connection with the cross-bar 25.

In order to insure the permanent parallelism of the needle with the needle-bar, the member 29 of the forked arm of the needle slide-block is made rigid and the arm 30 is made yielding, so that in taking up the wear upon the cross-bar 25 by means of the screw 31 the position of the needle will not be materially changed.

By the present construction, a simple connection is made between the crank-arm 54 of the needle-jogging rock-shaft 55 and the needle-carrying slide-block 28 without materially cutting away and weakening the bearing portion of the bracket-arm head, as the connection between the parts within and beneath such head is made only through the reciprocating bar 46 slidingly journaled within simple bearing apertures of the bracket-arm head.

Having thus set forth the nature of the invention, what I claim herein is:—

1. In a sewing machine, in combination, a needle-bar, a transverse guide-pin rigidly sustained by said needle-bar, a transverse guide element carried by said needle-bar and substantially parallel with said guide-pin, a needle-carrying block slidingly mounted upon said guide-pin with which it has bearing contact at the sides of said pin respectively adjacent and farthest from said guide-element and operatively engaging said guide element, and means for reciprocating said block lengthwise of said guide-pin.

2. In a sewing machine, in combination, a needle-bar, a transverse cylindrical guide-pin rigidly sustained by said needle-bar, a transverse guide element carried by said needle-bar and substantially parallel with said guide-pin, a needle-carrying block formed with a cylindrical aperture fitted to

said guide-pin and provided with a fork to embrace said guide element and with adjusting means for said fork, and means for reciprocating said block lengthwise of said guide-pin.

3. In a sewing machine, in combination, a needle-bar, a yoke sustained thereby and comprising a cross-bar constituting a guide element and laterally spaced depending members, a guide-pin sustained by and extending between the depending members of said yoke, a needle-carrying block slidingly fitted upon said guide-pin respectively at the sides of the latter adjacent and more remote from said guide-element of the yoke and having a fork embracing said guide element, and means for reciprocating said block lengthwise of said guide-pin.

4. In a sewing machine, in combination, a needle-bar, a yoke sustained thereby and comprising a cross-bar constituting a guide element and laterally spaced depending members, a cylindrical guide-pin sustained by and extending between the depending members of said yoke, a needle-carrying block formed with a cylindrical aperture fitted to said guide-pin and having a fork embracing said guide element of the yoke and a laterally projecting stud-pin, and means including a vibratory lever forked to embrace said stud-pin and mounted independently of said needle-bar for reciprocating said block upon the guide-pin.

5. In a sewing machine, in combination, a rotary bearing member, a reciprocating needle-bar carrying a laterally movable needle and journaled in and adapted to turn with said member, a segmental guide embracing and reciprocating lengthwise of the needle-bar and sustained independently of said needle-bar, and a lever engaging said guide and communicating from it to the needle lateral jogging movements.

6. In a sewing machine, in combination, a support, a rotary bearing member journaled therein, a reciprocating needle-bar journaled in and adapted to turn with said member, a laterally movable needle carried by said needle-bar, a segmental guide embracing the needle-bar, a reciprocating bar having said guide rigidly secured thereto and journaled in said support independently of said needle-bar, a lever fulcrumed on said bearing member and engaging said guide to communicate from it to the needle lateral jogging movements, and means for actuating the guide-carrying bar.

7. In a sewing machine, in combination, a support, a rotary bearing member journaled therein, a reciprocating needle-bar journaled within and adapted to turn with said member, a laterally movable needle carried by said needle-bar, a segmental guide embracing the needle-bar and having a groove in its inner face, means for reciprocating said

- guide lengthwise of the needle-bar, and an elbow-lever having a lateral arm carrying a stud entering the groove of said segmental guide and another arm operatively connected with said needle for communicating to it lateral jogging movements.
8. In a sewing machine, in combination, a bearing member, a reciprocating needle-bar journaled therein and having a laterally projecting element, a laterally movable needle-clamp block carried by said needle-bar and provided with a lateral stud-pin, a needle mounted in said block, means for reciprocating the needle-bar, means for imparting to the needle-clamp block lateral jogging movements, a rigid post carried by said member and having a guideway to which the laterally projecting element of the needle-bar is fitted, and a guide-arm also carried by said member and formed with parallel channels entered alternately by the stud-pin of said needle-clamp block.
9. In a sewing machine, in combination, a support, a rotary bearing member journaled therein, a reciprocating needle-bar journaled in said member and having a laterally projecting element, a laterally movable needle-clamp block carried by said needle-bar and provided with a lateral stud-pin, a needle mounted in said block, means for reciprocating the needle-bar, means for imparting lateral jogging movements to the needle-clamp block, a laterally grooved guide-post carried by said member and entered by the laterally projecting member of the needle-bar, and a guide-arm also carried by said member and formed with parallel channels adapted to be entered alternately by the stud-pin of said needle-clamp block.
10. In a sewing machine, in combination, a support, a rotary bearing member journaled therein, a reciprocating needle-bar, a yoke sustained by said needle-bar and comprising a cross-bar and laterally spaced depending members, a guide-pin sustained by and extending between the depending members of said yoke, a needle-carrying block slidingly mounted upon said guide-pin and having means for restraining it from turning thereon and provided with a lateral stud-pin, a needle mounted in said block, means for imparting lateral jogging movements to the needle-carrying block, a laterally grooved guide-post carried by said bearing member and embracing one of said depending yoke members, and a guide-arm also carried by said bearing member and formed with parallel channels adapted to be entered alternately by the stud-pin of said needle-carrying block.
11. In a sewing machine, in combination, a needle-bar, a transverse guide-pin rigidly sustained by said needle-bar, a transverse guide element carried by said needle-bar and substantially parallel with said guide-pin, a needle-carrying block slidingly mounted upon said guide-pin and provided with a forked arm having spaced members embracing said guide element and one of which is adapted to yield relatively to the other, an adjusting screw connecting said spaced members of the forked arm, and means for reciprocating said block lengthwise of said guide-pin.
12. In a sewing machine, in combination, a support, a rotary bearing member journaled therein, a reciprocating needle journaled in and adapted to turn with said member, a laterally movable needle carried by said needle-bar, a segmental guide embracing the needle-bar, a reciprocating bar carrying said guide and journaled in said support, a steady pin sustained by said support at the side of the needle-bar opposite the guide-carrying bar and entering an aperture in said guide, a lever engaging said guide and communicating from it to the needle lateral jogging movements, and means for actuating the guide-carrying bar.
